(57) **CLAIM**

The ornamental design for a candle bucket, as shown and described.

DESCRIPTION

FIG. 1 is a top, perspective view of a first embodiment of a candle bucket;

FIG. 2 is a front elevation view of the embodiment of FIG. 1;

FIG. 3 is a back elevation view of the embodiment of FIG. 1;

FIG. 4 is a right side elevation view of the embodiment of FIG. 1;

FIG. 5 is a left side elevation view of the embodiment of FIG. 1;

FIG. 6 is a top plan view of the embodiment of FIG. 1;

FIG. 7 is a bottom plan view of the embodiment of FIG. 1;

FIG. 8 is a perspective view of a second embodiment of a candle bucket;

FIG. 9 is a front elevation view of the embodiment of FIG. 8;

FIG. 10 is a back elevation view of the embodiment of FIG. 8;

FIG. 11 is a right side elevation view of the embodiment of FIG. 8;

FIG. 12 is a left side elevation view of the embodiment of FIG. 8;

FIG. 13 is a top plan view of the embodiment of FIG. 8;

FIG. 14 is a bottom plan view of the embodiment of FIG. 8;

FIG. 15 is a perspective view of a third embodiment of a candle bucket;

FIG. 16 is a front elevation view of the embodiment of FIG. 15;

FIG. 17 is a back elevation view of the embodiment of FIG. 15;

FIG. 18 is a right side elevation view of the embodiment of FIG. 15;

(Continued)

FIG. 19 is a left side elevation view of the embodiment of FIG. 15;
 FIG. 20 is a top plan view of the embodiment of FIG. 15;
 FIG. 21 is a bottom plan view of the embodiment of FIG. 15;
 FIG. 22 is a perspective view of a fourth embodiment of a candle bucket;
 FIG. 23 is a front elevation view of the embodiment of FIG. 22;
 FIG. 24 is a back elevation view of the embodiment of FIG. 22;
 FIG. 25 is a right side elevation view of the embodiment of FIG. 22;
 FIG. 26 is a left side elevation view of the embodiment of FIG. 22;
 FIG. 27 is a top plan view of the embodiment of FIG. 22; and,
 FIG. 28 is a bottom plan view of the embodiment of FIG. 22. The broken lines in the drawings depict portions of the candle bucket that form no part of the claimed design. The candle bucket is shown with a symbolic break in its length. The appearance of any portion of the article between the break lines forms no part of the claimed design.

1 Claim, 16 Drawing Sheets
